No. 809,860.

PATENTED JAN. 9, 1906.

C. M. TAYLOR, JR.,
MEANS FOR MAKING MILK PRODUCTS AND RECOVERING MILK FLUIDS,
APPLICATION FILED JULY 22, 1904.

UNITED STATES PATENT OFFICE.

CHARLES M. TAYLOR, JR., OF PHILADELPHIA, PENNSYLVANIA.

MEANS FOR MAKING MILK PRODUCTS AND RECOVERING MILK FLUIDS.

No. 809,860.

Specification of Letters Patent.

Patented Jan. 9, 1906.

Continuation of application Serial No. 160,304, filed June 6, 1903. This application filed July 22, 1904. Serial No. 217,648.

To all whom it may concern.

Be it known that I, CHARLES M. TAYLOR, Jr., a citizen of the United States, residing at the city of Philadelphia, in the county of Philadelphia and State of Pennsylvania, have invented 5 new and useful Means for Making Milk Products and Recovering Milk Fluids, of which the following is a specification.

One object of the present invention is to provide for making without agitation or fermentation a milk product comprising unbroken milk, fatty globules, or buttery constituents by what may be termed "selective" absorption and for recovering the non-buttery or 15 milky portions, such as skimmed milk and the like.

Another object of the invention is to provide an efficient, cleanly, and durable apparatus or appliance by means of which the 20 product may be made rapidly without undue labor and by means of which the skimmed milk and like fluids may be saved.

To these and other ends hereinafter set forth the invention comprises the improvements to 25 be presently described and finally claimed.

The nature, characteristic features, and scope of the invention will be more fully understood from the following description, taken 30 in connection with the accompanying drawings, forming part hereof, and in which—

Figure 1 is a perspective view illustrating the various parts of apparatus embodying features of the invention. Fig. 2 is a sectional view illustrating a portion of the apparatus 35 with the various parts assembled. Fig. 3 is a perspective view illustrating a modification of a portion of the apparatus, and Fig. 4 is a view illustrating another modification.

In the drawings, 1 is a receptacle, and 2 is a 40 detachable lid or cover for the same. As shown, the receptacle 1 is constructed of sheet metal, and its lid 2 is provided with a depending flange 3, by means of which it may be fitted comparatively tight, thus excluding dust 45 and the like from the interior of the receptacle when the lid is in place.

4 is a partition constructed of material impermeable by the fatty or buttery constituents and permeable by the non-buttery or milky 50 fluids. Blotting-paper is an example of such material, and it is shown in the drawings as folded up into box-like form. Beneath the partition 4 is arranged a non-absorbent spacing device or spacer having openings, channels, ducts, or drainage-fluid ways. 5 is an 55 example of such a spacer, and it is shown to

consist of a corrugated, and therefore channeled, sheet of metal provided at the high parts of the corrugations with apertures or drains and upon which the partition is superposed. A modification of such a spacer is 60 illustrated in Fig. 3, wherein is shown a corrugated strip or sheet 6, as of metal, and the spaces 7 between the folds constitute wells or 65 cells, and the openings at their ends constitute drains. In Fig. 4 the spacer is composed of intersecting plates or walls having drainage-fluid ways *a*. Obviously the construction of the non-absorbent spacer can be varied as 70 well as the materiel from which it is made, the purpose being to use such material as will not absorb the fluids which are to be recovered, and therefore metal, glass, hard rubber, and the like can be used. Furthermore, it is 75 also the purpose to have the spacer exert, so far as may be, a draining action in respect to such fluids and the partition 4, and this action is induced by the perforations, drains, or drainage-fluid ways shown.

In use the non-absorbent spacer is placed in 80 the receptacle 1, and there is superposed upon it the partition 4, which, if in the form shown on the drawings, can be secured to place by means of the clips 8. The fluid to be treated, which is of course usually cream and will be 85 so nominated, is placed in any known or convenient way upon the partition 4, which by reason of its described properties retains the buttery or fatty constituents and permits the 90 passage of fluids. The latter are by reason of the described action of the spacer delivered in the receptacle 1, from which they may be collected. In this way all of the constituents are saved and the operation is rendered very 95 simple and expeditious. At the same time the apparatus is capable of being readily cleaned and of almost unlimited reuse, with the exception of course of the partition 4.

It will be obvious to those skilled in the art to which my invention appertains that 100 modifications may be made in details without departing from the spirit thereof. Hence I do not limit myself further than the prior state of the art may require; but,

Having thus described the nature and objects of my invention, what I claim as new, and desire to secure by Letters Patent, is—

1. Apparatus of the class described comprising the combination of a partition impermeable to the buttery or fatty constituents and permeable to the other constituents, a 110 non-absorbent spacer, having drain-openings,

arranged in contact with one face of the partition, and devices for receiving the non-buttery constituents, substantially as described.

2. Apparatus of the class described comprising a receptacle provided with a lid, a non-absorbent spacer having drain-openings and arranged upon the bottom of the receptacle, and a partition arranged above the spacer and impermeable to the fatty or buttery constituents and permeable to the other constituents, substantially as described.

3. In apparatus of the class described the combination with a partition impermeable to

the fatty or buttery constituents and permeable to the other constituents, of a corrugated non-absorbent sheet provided with openings or drains, arranged in contact with one face of the partition, substantially as described. 15

In testimony whereof I have hereunto signed my name.

CHARLES M. TAYLOR, Jr.
